TONJES A. BOTH, OF STRATFORD, CONNECTICUT, ASSIGNOR TO THE CONNECTICUT ELECTRIC MANUFACTURING COMPANY, OF BRIDGEPORT, CONNECTICUT, A CORPORATION OF CONNECTICUT.

DESIGN FOR A THREE-POLE ENTRANCE-SWITCH BASE.

54,525.

Specification for Design.

Patented Mar. 2, 1920.

Application filed August 2, 1918. Serial No. 248,088. Term of patent 7 years.

To all whom it may concern:

Be it known that I, TONJES A. BOTH, a citizen of the United States, residing at Stratford, county of Fairfield, State of Connecticut, have invented a new, original, and ornamental Design for Three-Pole Entrance-Switch Bases, of which the following is a specification, reference being had to the accompanying drawing, forming a part thereof.

In the drawing, Figure 1 is a plan view of a three pole entrance switch base, showing my new design, and

Fig. 2 is a side elevation corresponding therewith.

What I claim is—

The ornamental design for a three pole entrance switch base, as shown.

In testimony whereof I affix my signature.
TONJES A. BOTH.
